RECORD CHANGING DEVICE FOR
PHONOGRAPHS

Heinrich Zimmermann, St. Georgen, Black Forest, Germany, assignor to Gebrüder Steidinger K.-G., St. Georgen, Black Forest, Germany, a firm

Application January 25, 1954, Serial No. 405,958

2 Claims. (Cl. 274—10)

The present invention relates to phonographs equipped with a device for the automatic change of records. The invention particularly concerns phonographs of this kind, wherein a stack of records is centrally supported above the turntable.

For the change of records a device has proved to be satisfactory which comprises within the centre post of the phonograph two groups of stack supports which are adapted to be moved out alternately from the centre post and are arranged a distance apart in an axial direction which corresponds to the thickness of a record. The stack supports are operated in such a manner that, during the playing of one record placed upon the turntable, the lower group of supports carries the stack of records, whilst the upper group of stack supports separate, when operated, the lowermost record from the stack and support the remaining stack for the time which is required for the discharge of the separated record on to the turntable. Various actuating mechanisms have been proposed in the past for the alternate actuation of the stack supports. According to one of these proposals an actuating shaft is disposed within the centre post, and this actuating shaft is controlled in turn by the record changing mechanism of the phonograph.

The present invention, which relates to the last-mentioned construction, is to be seen in that the stack supports are formed by tongue-like springs which, if firmly connected to the centre post, co-act with deflecting faces or deflecting cams of the axially displaceable actuating shaft, or, if connected to the actuating shaft, co-act with stationary deflecting surfaces. The advantage of stack supports constituted by springs is to be seen mainly in that bearings can be avoided.

A record-changing device of this kind has proved to be particularly advantageous wherein only the upper group of stack supports is formed by tongue-like springs, which are fastened to the axially shiftable actuating shaft and co-act with stationary deflecting surfaces within the centre post, whilst the lower stack supports are formed by fingers which are carried by pivotally supported levers extending in an axial direction. With this construction it is advisable to place the pivotally supported levers under the influence of spring means, which are arranged to urge the supporting fingers of the levers into the supporting position. Moreover, the arrangement can be made advantageously such, that the stack supports of the lower group, when they are withdrawn from their operative position, are adapted to support the upper group of stack supports when they are in their supporting position.

It is advantageous to connect the centre post with the stack supports to the turntable in an exchangeable manner in order to make it possible to use the phonograph in the conventional manner without a record-changing device. It may be mentioned that the record-changing device according to the invention is suited to be used mainly for phonographs which are adapted for playing records with a large centre hole. With such apparatus

2

the centre posts have a correspondingly large diameter so that there is ample space in their cavity to accommodate the stack supports; however, the construction of the record-changing device according to the invention is not limited to centre posts with large diameters. The construction of the changing device according to the invention and particularly its operation can also be realised with centre posts of smaller diameter.

An embodiment of the invention will now be described by way of example in more detail with reference to the accompanying drawings, wherein:

Fig. 1 shows a longitudinal section of a phonograph centre post, the lower group of stack supports being in the supporting position, whilst

Fig. 2 illustrates a longitudinal section corresponding to that of Fig. 1, which shows the stack supports of the upper group in the supporting position.

As shown, a centre post 1, which has a removable upper portion 2, is provided with a cylindrical cavity and with a central bore through which an actuating shaft 3 extends. The actuating shaft carries in the lower part of the cavity a truncated cone 4, whilst to its upper end springs 5 and 6 are fastened which bear against bent surfaces 7 and 8 at the lower end of the member 2. Levers 13 and 14 are pivotally supported on pins 9 and 10 and biased by springs 11 and 12. The upper ends of the levers are shaped to form supporting fingers which project in the position shown, laterally through openings of the centre post 1 and serve as supports of a stack of records held in a central position by the upper part 2 of the centre post.

In the position shown in Fig. 1 the levers 13 and 14 support the stack of records. On the other hand, in the position shown in Fig. 2, the levers 13 and 14 are angularly displaced so that their supporting fingers are withdrawn into the cavity of the centre post, whilst the springs 5 and 6 project with their ends laterally out of the centre post. Accordingly, the springs 5 and 6 are in a position to take over the support of the stack of records.

The shifting of the stack supports from the position according to Fig. 1 into the position shown in Fig. 2 is caused by an upward movement of the actuating shaft 3. As a result of this upward movement, the truncated cone 4 forces the lower arms of the levers 13 and 14 apart, so that the upper ends of these levers are displaced inwardly. At the same time the springs 5 and 6, by being deflected along the curved surfaces 7 and 8, are forced to move outwards from their covered position shown in Fig. 1, so that they project out of the centre post. The springs 5 and 6 are disposed above the levers 13 and 14, and the arrangement is made such that the inwardly displaced ends of the levers 13 and 14 support the outwardly projecting springs 5 and 6. In this way the supporting power of the springs 5 and 6 is substantially increased, so that they are suited to carry safely the stack of records even if of light construction.

The springs 5 and 6 are so arranged above the levers 13 and 14 that their ends, which serve for the support of the stack of records, are displaced with respect to the supporting fingers of the levers 13 and 14 a distance which corresponds to the thickness of a record. Accordingly, when the actuating shaft 3 is moved upwards, the ends of the springs 5 and 6 will enter between the two lowermost records of the stack, so that the lowermost record is separated from the stack and free to fall down upon the turntable as soon as the levers 13 and 14 are caused by the truncated cone 4 to move into the position shown in Fig. 2.

The lower edge of the supporting fingers of the levers 13 and 14 may be so shaped that, when the played

records are removed from the turntable, these levers 13 and 14 give way and do not impede the removal of the records.

What I claim is:

1. A record changing device for phonographs of the type having a turntable with means for supporting a stack of records thereabove, said device comprising, a hollow center post mounted centrally of said turntable, a set of flat-type elongate springs within said post, means forming a set of guide elements within said post, shaft means axially shiftable within said post, one of said sets being fixed on said post and the other of said sets being secured to said shaft means, said springs being resiliently deformed in generally opposite radial directions and having free end portions engaging against said guide elements, said guide elements being curved and flared outwardly in generally opposite directions radial of said post, said springs being resiliently deflectable radially outwardly responsive to relative closing movement of said springs and guide elements, said end portions of said springs being arranged to project generally radially outwardly of said post and into the interstices between adjacent records when said springs and guide elements are in relatively closed relation, whereby to separate the lowest record from a stack and to support the remaining records, said end portions being arranged to be retracted within said post when said guide elements and springs are in relatively open relation, said guide elements having radii of curvature smaller than the radii of curvature of said springs in outwardly deflected condition so that the free end portions only of said springs engage said guide elements with intermediate portions of said springs remaining free of said guide elements, whereby to facilitate flexing of said springs upon obstruction of their radially outward movement and a consequent vertical searching action of said end portions responsive to continued axial progress of said shaft means, whereby to insure penetration thereof between adjacent records, second record support means mounted within said post and being shiftable selectively to a record supporting position and to a retracted position, said second support means in record supporting position being spaced from said end portions of said spring by a distance generally corresponding to the thickness of a record, and means associated with said shaft means operable to shift said second support means to said positions alternatively to said springs.

2. A record changing device for phonographs of the type having a turntable with means for supporting a stack of records thereabove, said device comprising a hollow center post mounted centrally of said turntable, a set of flat type elongate springs within said post, means

extending outwardly in generally opposite directions generally radial of said post, said springs having free end portions engaging against said guide elements, said guide elements holding said springs resiliently deformed in generally opposite radial directions, said springs being resiliently deflectable radially outwardly responsive to relative closing movement of said springs and guide elements, said end portions of said springs being arranged to project generally radially outwardly of said post and into the interstices between adjacent records when said springs and guide elements are in relatively closed relation, whereby to separate the lowest record from a stack and to support the remaining records, said end portions being arranged to be retracted within said post when said guide elements and springs are in relatively open relation, said springs having portions intermediate their fixed portions and their points of engagement with said guide elements, said intermediate portions of said springs being free to flex responsively to obstructed outward movement of the end portions of said springs with a consequent vertical searching action of said end portions responsive to continued relative axial movement of said shaft means and post, whereby to insure penetration of said end portions between adjacent records, second record support means mounted within said post and being shiftable selectively to a record supporting position and to a retracted position, said second support means in record supporting position being spaced from said end portions of said spring by a distance generally corresponding to the thickness of a record, and means associated with said shaft means operable to shift said second support means to said positions alternatively to said springs.
